S. THORP.
COUPLING CARS.

No. 36,247.

Patented Aug. 19, 1862.

UNITED STATES PATENT OFFICE

STILLMAN THORP, OF TURNER, MAINE.

IMPROVEMENT IN CAR-COUPINGS.

Specification forming part of Letters Patent No. 36,247, dated August 19, 1862.

To all whom it may concern:

Be it known that I, STILLMAN THORP, of Turner, in the county of Androscoggin and State of Maine, have invented a new, useful, and Improved Method of Self-Coupling Cars; and I do hereby declare that the following is a full and exact description thereof, reference being had to the accompanying drawing, and to the figure and letters of reference marked thereon.

The figure is a view of the platform of two adjacent cars having my improvement attached.

The danger to which operatives upon railroads are exposed of being jammed between the cars when engaged in coupling them together renders some efficient method of guiding the coupling-link into the buffer-head or spring draw-bar without the necessity of taking hold of the link by the hand exceedingly desirable. For this purpose I have invented the following simple and mechanical means, to wit: a chambered box or tube to hold the link, and which is made to slide into and out of the mouth of the spring draw-bar at pleasure, and so contrived that the link is supported and guided into the mouth or opening of the opposite buffer whenever the cars are brought into contact with each other and without requiring the aid of the operative or rendering it necessary for him to be between the cars as they approach each other.

To enable others to understand my invention, I will proceed to describe the manner in which I have carried it out.

In the accompanying drawing, A A are the adjacent platform cars to be coupled together, and B B the spring draw bars attached thereto.

C C represent the buffers as detached from draw-bars B B, and attached to D, my invention consisting of a sliding chambered box or tube, as applied to draw-bars B B, one of which, and holding the link M, is pressed into the draw-bar B to its shoulder and shackled thereto, and the other box, D, partly drawn from the opposite draw-bar, B.

i is the coupling-pin, shown in elevation and resting upon box D, ready to fall and effectually connect the cars as soon as the buffers of

the two adjacent and approaching cars are pressed together.

P shows the coupling-pin slot.

R shows my invention complete with the buffer C attached thereto.

E is a sectional view showing half of the same with its inner construction, and n is the chamber in which one end of the link M is placed prior to shackling the cars. This chamber holds and directs the link M into the mouth of the opposite draw-bar when the two approaching cars A A meet.

X is a slot back of the chamber through which to pass a moving pin, if required, to prevent the tube D from falling out of draw-bar B when unshackled.

Some of the advantages in my invention are as follows, to wit: First, it will cost no more newly made than do common draw-bars; second, on repairs it will be less expensive, for by its use money, time, and labor will be saved by removing the broken and inserting a new box; third, a car having my invention attached works in connection with another having the common draw-bar, attached with equal facility; fourth, it can be applied to both ends of the cars, and thereby operate in every respect like the draw-bars in common use; fifth, it is a self-coupler, and therefore, being a self car-coupling invention and a saving of labor, time, money, life, and limbs, it calls loudly for railroad corporations to encourage its general use; sixth, it can be applied to a capped wrought-iron bar as well as to a flaring draw-bar.

I do not claim buffer C; but

What I do claim, and desire to secure by Letters Patent, is—

The chambered sliding box or tube D, attached to buffer C, applied to and operating in connection with draw-bar B, link M, and coupling-pin i, substantially as set forth, for the purpose specified.

STILLMAN THORP.
